UNITED STATES PATENT OFFICE.

CHARLES E. BONYATA, OF GRINNELL, IOWA.

BUBBLE FORMING AND BLOWING DEVICE.

Application filed January 2, 1924. Serial No. 684,052.

To all whom it may concern:

Be it known that I, CHARLES E. BONYATA, a citizen of the United States, residing at Grinnell, in the county of Poweshiek and State of Iowa, have invented certain new and useful Improvements in Bubble Forming and Blowing Devices; and I do declare the following to be a full, clear, and exact description of the invention, such as will enable others skilled in the art to which it appertains to make and use the same.

My invention has for its principal object to provide a simple, inexpensive, cheaply operable, and very attractive device to form bubbles from a liquid, for instance, a liquid shampoo, and blow such bubbles about in a show window or the like, for the purpose of providing a distinctive advertisement.

With the foregoing in view, the invention resides in the novel subject matter herein-after described and claimed, the description being supplemented by the accompanying drawing.

Figure 1 is a vertical sectional view partly in elevation showing a bubble forming and blowing device constructed in accordance with my invention.

Figure 2 is a horizontal sectional view on line 2—2 of Fig. 1.

In the drawing above briefly described which illustrates the preferred form of construction, the numeral 1 designates a substantially flat pump casing which may well be supported upon suitable legs 2, the lower side of said casing being shown as formed with an air inlet eye 3. Supported upon the casing 1, I have illustrated a vertical electric motor 4 whose shaft 5 extends into said casing and is provided with a pump rotor 6.

The motor may be secured upon the casing 1 in any desired manner, but I have shown it provided with an outstanding flange 7 through which attaching bolts 8 pass.

Upon the upper end of the motor shaft 5, I have illustrated a fan 9 surrounded by a guard 10 which is supported by the motor 4. A liquid tank 11 is provided to contain the liquid from which the bubbles are to be formed and in the present showing, this tank is supported upon the guard 10, to one side of the fan axis. This tank may be provided with any suitable filling cap or the like

12, with a bubble outlet 13; and with an air inlet 14. This inlet is connected by a pipe 15 with the pump casing 1 and a suitable valve 16 is provided in said pipe to control the amount of air passing therethrough. If desired, the pipe 15 may also be provided with a check valve (not shown) to prevent any liquid from running therethrough, from the tank 11, if the valve 16 is inadvertently left open when the device is not in operation.

In operating the device, the liquid is placed in the tank 11 and the motor 4 is set into operation. The pump rotor 6 forces a current of air up through the pipe 15 into the liquid in the tank 11, to aerate the latter and form bubbles, which bubbles escape through the bubble outlet 13 and are caught by the upward draft of air from the fan 9, so that they are blown from the device, thereby producing a very distinctive display for advertising purposes.

As excellent results are obtainable from the details disclosed, they may well be followed, but within the scope of the invention as claimed, numerous changes may be made.

I claim:

1. A bubble forming device comprising a pump casing, a motor supported thereon, a pump rotor in said casing connected with the motor shaft, a fan on the upper end of said motor shaft for directing a current of air upwardly, a liquid tank having a bubble outlet over said fan, and an air pipe from said pump casing into said liquid tank to admit air into the latter and form bubbles for discharge through said bubble outlet into the air current.

2. A bubble forming device comprising a pump casing, a motor supported thereon, a pump rotor in said casing connected with the motor shaft, a fan on the upper end of said motor shaft for directing a current of air upwardly, a liquid tank having an air inlet leading from said pump casing and also having a bubble outlet over said fan, and a guard around said fan supported by said motor and in turn supporting said tank.

In testimony whereof I have hereunto affixed my signature.

CHARLES E. BONYATA.
